THE NORRIS PETERS CO., WASHINGTON, D. C.

UNITED STATES PATENT OFFICE.

WILLIAM F. VOLKENANT, OF LESTER PRAIRIE, MINNESOTA.

FENCE-MAKING MACHINE.

No. 853,660.

Specification of Letters Patent.

Patented May 14, 1907.

Application filed February 12, 1907. Serial No. 356,974.

To all whom it may concern:

Be it known that I, WILLIAM F. VOLKENANT, a citizen of the United States, residing at Lester Prairie, in the county of McLeod 5 and State of Minnesota, have invented certain new and useful Improvements in Portable Fence-Making Machines; and I do hereby declare the following to be a full, clear, and exact description of the invention, such 10 as will enable others skilled in the art to which it appertains to make and use the same.

My invention has for its object to provide a simple and efficient portable fence making 15 machine especially adapted for making wire fence on the posts or in the position in which it is to be used.

To the above ends the invention consists of the novel devices and combinations of 20 devices hereinafter described and defined in the claims.

In the accompanying drawings which illustrate the invention, like characters indicate like parts throughout the several views.

Referring to the drawings, Figure 1 is a 25 view in side elevation, showing the improved fence making machine or device in operative position, and illustrating the action thereof in making a fence. Fig. 2 is a view in side elevation, but on a larger scale than in Fig. 1, showing the fence making machine removed from working position. Fig. 3 is a front elevation of the device, some parts being broken away. Fig. 4 is a transverse section taken 30 on the line $x^4 x^4$ of Fig. 3. Fig. 5 is a front elevation of one of the so-called "twisters," and Fig. 6 is a rear elevation of the said twister.

The numeral 1 indicates a channel bar 40 which is supported in an upright position, preferably by means of a shoe or ground bracket 2 secured to the lower end thereof and adjustably connected to the intermediate portion thereof by a brace rod 3, which 45 brace rod telescopes into the up-turned arm 2^a of said shoe and is rigidly but adjustably secured thereto by a set screw 4. By adjustments of the rod 3 with respect to the arm 2^a , the channel bar 1 which constitutes 50 the body support of the fence machine may be set in a vertical position even when the underlying ground is on an incline.

The body web of the channel bar 1 is perforated at the desired point longitudinally 55 thereof and is provided with bearing collars 5. These bearing collars 5 are slightly reduced

at one end to fit the large perforations in the channel bar 1, and the reduced ends are slightly upset, thereby rigidly securing the bearing sleeves 5 to the said channel bar. 60 Loosely journaled in each bearing sleeve 5 is a rotary twister sleeve 6, one end of which is flanged for engagement with the reduced end of the bearing sleeve 5. To the other end of said twister sleeve 6 is secured a worm gear 65 7. This worm gear 7 is preferably secured to the twister sleeve 6 by a pair of nutted bolts 8, which bolts are passed through a transverse web 6^a of said sleeve 6 and through a transverse web 7^a of said gear 7. The said 70 webs 6^a and 7^a are each formed, respectively, with diametrically opposite line wire passages 6^b and 7^b, which passages 6^b and 7^b align with each other. Each twister head made up of the co-operating sleeve 6 and gear 7 carries a 75 spreader which is preferably in the form of an approximately T-shaped bracket 9, the base flanges of which are rigidly secured to the web 7^a of the gear 7 by the nutted bolts 8 before described. The extended cross arm of 80 the spreader bracket 9 is formed by a pair of laterally spaced straps, between the ends of which are journaled small guide sheaves 10.

Mounted in suitable bearings 11 and extending approximately from end to end of 85 the channel bar 1, is a shaft 12 that is provided with worms 13. In the construction illustrated, the five lower twistlers are located so close together that their gears 7 intermesh 90 with each other. Hence, one worm 13 meshing with one of said lower gears 7 serves to impart rotary movement to the five lower twistlers. One worm 13 meshes with each of the gears 7 of all of the twistlers above the lower five. At its intermediate portion, said 95 shaft 12 is also provided with a bevel pinion 14 that meshes with a bevel gear 15 mounted in a suitable bearing yoke 16 secured to said channel bar 1. A crank lever 17 is secured to and for rotation with the bevel gear 15. 100 As is evident, simultaneous rotary movements may be imparted to the several twistlers by rotation of the crank 17. The numeral 18 indicates webs shown as secured to the back of the channel bar 1.

The numeral 19 indicates hooks shown as applied to the upper arm 2^a of the shoe 2, and which hooks are engageable with certain of the line wires to assist in supporting the device in working position.

In Fig. 1, the line wires of the fence are indicated by the letter a and the pickets or stay

wires are indicated by the letter *b*. The line wires *a* are arranged in pairs and may be assumed to be stretched from post to post in approximately the positions they occupy in 5 the completed fence. The line wires *a* are extended through the passages 6^b and 7^b and over the guide sheaves 10 of the twisters, as shown in Fig. 1, and the said line wires are twisted together in pairs by simultaneous rotary movements of the several twisters under 10 the action of the crank 17. When the several wires have been twisted together for a distance representing the space between pickets or stay wires *b*, a picket is placed in position 15 at the forward terminations of the several twists and then the machine is moved ahead slightly, and the twisters are then rotated in a reverse direction until the said wires have been twisted together a distance 20 proper for the application of the next stay or picket. In this way, as is evident, the fence is formed with line wires, the twists of which are alternated between successive stays or pickets.

25 By a machine of the kind described, wire fence may be rapidly constructed at the exact place where it is intended for use. Said machine is of small cost and, hence, will find extensive sale where more expensive machines would not be sold.

What I claim is:

1. In a machine of the kind described, the combination with an extended body support, of a plurality of twisters rotatively mounted thereon, each of said twisters comprising a gear, a detachably connected flanged bearing sleeve and a spreader bracket, which

parts of said twisters are provided with guides and passages for the wire to be twisted, and a crank driven shaft mounted on said body support and provided with worms meshing with the gears of said twisters, substantially as described. 40

2. In a device of the kind described, the combination with a body support 1 having a plurality of vertically spaced sleeves 5 rigidly secured thereto, flanged sleeves 6 journaled in the said sleeves 5, gears 7 detachably secured to said sleeves 6, spreader brackets 9 secured to said gears and provided with a head made up of laterally spaced metal straps and interposed sheaves 10, a shaft 12 journaled in bearings on said support 1 and provided with worms meshing with said gears 7, and a crank mounted in the bearing on said 45 bar 1 and geared to said shaft 12, substantially as described.

3. In a device of the kind described, the combination with an upright body support and a plurality of twisters mounted thereon, 60 of a shoe 2 attached to the lower end of said upright body support and provided with an up-turned arm 2^a, and an adjustable brace rod 3 attached to the intermediate portion of said upright body support and telescoping 65 with and adapted to be secured in different positions with respect to the said arm 2^a, substantially as described.

In testimony whereof I affix my signature in presence of two witnesses.

WILLIAM F. VOLKENANT.
